GRINDING WHEEL PROFILE DRESSING DEVICE

Nikolaus Engelmann, Philadelphia, Pa.

Application June 6, 1950, Serial No. 166,422

7 Claims. (Cl. 125—11)

1

My invention relates to new and useful improvements in grinding wheel profile dressing devices in which a lever, journalled for universal movements by a ball and socket joint adjacent the head end of said lever, the tail end of which operates over a form template, supports a dresser diamond or cutting element to the rear of but adjacent the location of the journal or pivot point which diamond is spaced in a predetermined ratio relative to the template holder and/or the working edge of said template and said journal. By mounting the template in either one of two slots, eleven and twelve inches, respectively, from the center of the pivot or journal and ten inches from the center of the diamond cutter, a five-to-one and a ten-to-one ratio of reduction will be accomplished.

An object of my invention is to produce a simple and compact structure that will transfer a true outline from the template to the resulting profile 20 of the grinding wheel.

Another object of the invention is to produce a structure of this kind having means to properly adjust the various elements prior to or at approximately the time of beginning the profile dressing operations on the grinding wheel.

Another object of this invention is to produce a structure capable of novel adjustments whereby small sharp corners and angles may be readily and easily formed in the profile during the dressing operations.

Another object of the present invention is to provide a diamond holder in the form of a crank for adjusting the diamond cutter to either side of the longitudinal center of the universally movable pivoted lever whereby further and extraordinary profile features may be dressed into the grinding wheel and the ratio of reduction between the template and diamond cutter can be changed.

Another object of the invention is to provide means for temporarily holding the lever rigidly on the pivoting ball and socket joint to allow adjustment of the chisel pointed follower for the template relative to the latter before starting the dressing operations.

Another object of this invention is to mount the pivoting ball structure on a horizontal pivot whereby the ball and component and associated elements can be swung angularly to either side 50 of the perpendicular for producing otherwise difficult formation in the grinding wheel.

A further object of the invention is to provide novel means for closing the opening in the bottom of the lever through which the neck of the pivoting ball passes.

2

A still further object of the invention is to produce a plurality of arcuate slots in the rear part of the base to selectively hold a template in definite relationship to the pivot point of the lever and the diamond cutter thereon.

With the above and other objects in view this invention consists of the details of construction and combination of elements hereinafter set forth and then designated by the claims.

In order that those skilled in the art to which this invention appertains may understand how to make and use the same I will describe its construction in detail, referring by numerals to the accompanying drawing forming a part hereof,

in which:

Fig. 1 is a side view of a grinding wheel profile dressing device constructed in accordance with my invention and shown in relation to a grinding wheel being dressed, portions of the device being illustrated in section to depict some of the details of construction.

Fig. 2 is a top plan view of the device also with parts shown in section.

Fig. 3 is a front or head end view of the device as illustrated in Fig. 1.

Fig. 4 is a section on the line 4—4 of Fig. 1.

Fig. 5 is a plan view of the sectional or two-piece dust guard.

In carrying out my invention as herein embodied 10 represents a base frame to be mounted on any suitable supporting surface 11 adjacent a grinding wheel 12 which is to be dressed to any desirable formation on the periphery thereof.

The base frame includes a body 13, preferably having underneath hollowed out chambers for reducing the weight thereof, an upwardly projecting arm 14 at the head end and an upwardly extending enlargement or tail fluke 15 at the rear end having a pair of spaced transversely extending arcuate slots 16 and 17 in the upper portion thereof. Suitable set screws 18 are associated with both slots, the same being threaded into the tail fluke from opposite faces, front and rear, so as to enter their respective adjacent slots and engage a thin template 19 selectively mounted in one of said slots.

In a head arm 14 is a stud or pivot 20 on which is swingingly mounted the ball structure 21 of a ball and socket joint. The ball structure 21 consists of a finger or pointer 22, a shank 23 extending in a straight line from the upper end of said finger and a ball 24 at the outer end of the shank.

A dressing lever 25 is of any desirable configuration but, preferably, is rectangular in cross sec-

tion and the tail end is tapered. In the head end of the lever is formed a longitudinal bore 26, the inner or bottom end of which is semi-spherical in shape, and a longitudinal slot 27, Fig. 1, is provided on the underneath side of the lever running from the terminal head end towards the tail end thereof and communicating with and substantially commensurate in length to said bore.

A sliding block 28 is mounted in the bore 26 and has a semi-spherical surface opposed to the bottom wall of the bore 26 and forms with said bottom wall, a socket to receive the ball 24 and thus provide a ball and socket joint for the mounting of the dressing lever. The block 28 is retained in engagement with the ball by a spring 29 having one end resting against the outer end of the block and the other end engaging a cap 30 screwed onto the head end of the dressing lever 25 to close the open end of the bore 26 and a part of the slot 27. The tension of the spring 29 can be varied by adjusting the cap 30 longitudinally of said dressing lever 25. That portion of the slot 27 not covered by the cap and not occupied by the shank of the ball and socket joint structure is covered by the sectional or two-piece dust guard, Fig. 5, including a forward plate 31 having an aperture 32 in one end for registration with the shank 23 and a corrugated finger 33 at the opposite end of a width small enough to pass through the slot 27 and engage the inside of the cap 30. In addition, the dust guard includes a companion rear plate 34 having an aperture 35 in one end to register with the shank 23 while the other end of said rear plate is plain and held in place on the under side of the dressing lever 25 by a clip 36, Fig. 1, secured to said lever slightly to the rear of the inner end of the slot 27. The apertured ends of the plates constituting the dust guard overlap so that solid portions of one plate closes the aperture of the other plate beyond the shank 23.

To temporarily fix the dressing lever 25 in a predetermined position a rod 37 is slidably mounted through holes in the cap 30 and sliding block 28 for projection into a hole in the ball 24, the latter hole being in the longitudinal axis of the dressing lever when said axis is horizontal and parallel to the longer sides of the base frame 10. On the outer end of the rod 37 is a stop 38 located outside of the cap 30 and a second stop 39 also is mounted on the rod intermediate its ends and located on the inside of said cap. These stops coact with the cap to prevent detachment of the rod 37 from the said cap but are spaced sufficiently to allow adequate movements for engaging said rod with and disengaging same from the ball.

In the body of the dressing lever 25 adjacent the ball and socket joint are formed two vertical holes 40 and 41 located in the longitudinal center of said lever and spaced a definite distance apart and from the ball and socket joint relative to other elements of the apparatus. Set screws 42 and 43 are threaded into the dressing lever body from either side thereof to project into the holes 40, 41, respectively, and hold any tool or tool holders in place therein.

The dressing lever 25 also has a pair of vertical holes 44 and 45 therein adjacent the tail end and these are also in the longitudinal center of the lever and spaced the same as the holes 40 and 41 so that the axes of said holes 44, 45 are directly above or in line with the arcuate slots 16, 17 respectively. Set screws 46 and 47 are threaded into the dressing lever from either side

thereof to project into the respective holes 44, 45 and hold any rod-like article in place therein. A suitable knob 48 is mounted on the tail end of the dressing lever for conveniently manually operating said lever over the pattern edge of the template.

A cutting tool 49, usually provided with a diamond point 50 is selectively placed in either of the holes 40, 41 and temporarily secured by the proper set screws 42, 43 or said cutting tool may be inserted in a hole 51 in the outer end of the crank arm 52 and fastened by the set screw 53 threaded into said crank arm so as to project into the hole 51 and hold the cutting tool in place. The crank arm 52 is provided with a crank pin 54 which is inserted in either hole 40, 41 and fastened by a screw 42, 43 after the crank arm has been adjusted to a desired position.

A chisel pointed follower 55 is selectively mounted in one of the holes 44, 45 and temporarily securely held in place by one of the screws 46, 47 after the desired or necessary longitudinal adjustment has been made.

The finger or pointer 22 is provided at its free end with a suitable formation 56, such as an index mark, for cooperation with a set of indication marks 57 on the front face of the head end of the body frame, said indication marks representing angular degrees at which the ball structure and dressing lever can be swung sidewise.

From the foregoing it will now be apparent that I have produced an exceedingly simple, compact, strong and efficient grinding wheel profile dressing device in which the dressing lever may be universally swung on its ball and socket joint laterally or horizontally and perpendicularly or vertically from its tail end whereby the follower will travel over the edge formation of the template to reproduce a desired contour on the circumferential surface of the grinding wheel by means of a cutting tool mounted on said dressing lever adjacent to the ball and socket joint but between said joint and the location of the template. The cut formations on the grinding wheel will be of smaller dimensions than the template formations due to the difference in movements of the tail end of the lever and that portion thereof in the region of the location of the cutting tool. The ratio may be easily changed by placing the cutting tool in either of two tool receiving holes and locating the template in either of the two template receiving slots and positioning the follower for cooperation therewith. An additional adjustment can be accomplished by using the tool holder and swinging it to one side or the other of the longitudinal axis of the lever. Further, sharp angular and odd surfaces may be cut by swinging the ball structure on its pivot which will move the dressing lever to one side of the perpendicular, the angle being shown on the scale of indication marks.

In actual practice, the apparatus is positioned relative to a grinding wheel to be dressed and the rod 37 is projected into the hole in the ball so that the dressing lever will be temporarily held in a straight line. The follower is then adjusted until its chisel end engages the upper edge formation. Thereafter the rod 37 is withdrawn from the ball and the dressing lever is released for operation and by moving either the dressing device or grinding wheel towards one another and moving the follower over the template the desired profile will be cut into said grinding wheel.

Of course I do not wish to be limited to the

exact details of construction herein shown and described as these may be varied within the scope of the appended claims without departing from the spirit of my invention.

Having described my invention what I claim as new and useful is:

1. A grinding wheel profile dressing device comprising a frame having an upright arm at the head end and provided with means at the tail end to hold a template, a ball structure including a finger, a shank and a ball, means passing through the head arm and finger to swingingly adjustably mount the ball structure on the frame, a lever having a longitudinal bore in the head end and a slot on the underneath side of said lever and communicating with and of the same length as said bore, the bottom of said bore being semi-spherical to constitute a portion of a socket for the ball, a block slidably mounted in the bore and provided with a semi-spherical surface opposed to the bottom wall of said bore and forming therewith the complete socket to receive the ball with the shank in the slot, means to hold the block in the bore of the lever, said means including a cap detachably mounted on the head end of the lever and a spring in the bore engaging said cap and block said lever having two separate pairs of holes therethrough all in parallel relation to one another and in line with an axis through the ball and its shank and finger, one pair at the tail end of said lever and the other pair adjacent the ball and socket joint between it and the holes at the tail end, the holes of each pair being spaced and the same distances, a grinding wheel cutting means selectively mounted in either one of the pair of holes adjacent the ball and socket joint, and a follower having a chisel point selectively and adjustably mounted in either one of said other pair of holes.

2. The dressing device according to claim 1, in combination with a dust guard comprising two coacting plates having apertures to register with the shank of the ball structure and positioned in overlapping relation on the lever beneath the slot in the head of said lever, and means to hold the parts of the dust guard in place said means including a corrugated finger projecting from the outer end of one plate and projecting into the slot in the underneath side of the lever and entered into the cap, and a clip fastened to the underneath side of said lever to the rear of the slot and engaging the rear end of the other plate.

3. The dressing device according to claim 1 wherein the grinding wheel cutting means includes a crank shaped tool holder selectively mounted in either one of the pair of holes adjacent the ball and socket joint, and a cutting tool including a diamond removably mounted in the tool holder.

4. The dressing device according to claim 1, in

combination with a rod longitudinally slidably in the head of the lever and extending through the sliding block for projection into a hole in the ball when said lever is in a straight line relative to the frame.

5. The dressing device according to claim 1 wherein the terminal of the finger has a formation to function as a pointer, in combination with indication marks on the frame and with which the pointer formation cooperates to indicate the angular position of the ball and socket joint.

6. A grinding wheel profile dressing device comprising a base frame having an upright arm at the head end and an upwardly extending enlargement at the tail end, a ball of a ball and socket joint pivotally mounted on the upright arm, said enlargement having spaced curved slots in the upper portion thereof in arcs of radii whose axis is in the center of the ball, a template selectively mounted in either of said curved slots, in combination with a lever having a longitudinal bore in the head end thereof and provided with a slot on the underneath side of said lever and communicating with and of the same length as said bore, the bottom of said bore being semi-spherical to constitute a portion of a socket for a ball joint, a block slidably mounted in the bore and provided with a semi-spherical surface opposed to the bottom wall of said bore and forming therewith the complete ball socket in which the ball is mounted, a screw cap threaded on the head end of said lever, and a spring in the lever bore between the screw cap and sliding block to urge the latter towards the ball.

7. The structure according to claim 6 wherein the pivoting means for the ball of the ball and socket joint includes a generally pendent shank projecting from the ball, a stud carried by the arm and extending from the forward face thereof and on which the shank is mounted for oscillation laterally of the base frame, and a finger extending in a straight line from said shank for cooperation with indicia on said forward face of said upright arm.
